UNITED STATES PATENT OFFICE.

WILLIAM A. EHLMAN, OF MILWAUKEE, WISCONSIN.

IMPROVEMENT IN COMBINED CHAIR AND DESK.

Specification forming part of Letters Patent No. **56,540**, dated July 24, 1866.

To all whom it may concern:

Be it known that I, WILLIAM A. EHLMAN, of the city and county of Milwaukee, and State of Wisconsin, have invented a Combined Easy-Chair and Writing-Desk; and I do hereby declare that the following is a full, clear, and exact description thereof, which will enable others skilled in the art to make and use the same, reference being had to the accompanying drawings, forming part of this specification.

The present invention consists in so attaching the back of an easy or other chair to its body that, when so desired, it can be swung over and into a horizontal position, or nearly so, with its rear side uppermost, and there supported or sustained, leaving the seat portion of the chair free, so that it can be used for the purpose of a writing desk or table, as will be apparent from the following detail description thereof, reference being had to the accompanying plate of drawings, in which—

Figure 1 is an elevation of one side of an easy-chair when its back is in an upright or vertical position; and Fig. 2, also, a side view of the easy-chair, showing its back swung down into a horizontal position, or nearly so, so that it can be used for the purposes of a writing desk or table.

Similar letters of reference indicate like parts.

A in the drawings represents the seat portion of the chair-frame, which may be upholstered in any desired style or manner, and is supported upon four legs, B, one at each corner. To each of the front legs is pivoted the lower ends of curved or bent supports c, that at their upper ends are similarly pivoted to the outer ends of the curved side arms, D, for the chair-seat, pivoted by their other ends to the sides of the chair-back E, which at its lower end rests upon the back rail, F, of the seat-frame A, inside of the flange-strip G, secured therein. The supports c sustain the arms of the chair-seat at their front ends, which arms, by means of bent hook-arms H,

hung in the side strips, I, of the seat-frame, when hooked into the eyes J, upon the under side of the chair-arms, are firmly held in position.

From the above description of the manner in which the back and arms of the chair are connected together and to the front legs, it is plainly obvious that if the hook-arms H be disengaged from the eyes upon the under side of the chair-arms, the back of the chair can be then swung over toward and behind the front of the chair-seat, and into a horizontal position, or nearly so, with its rear side uppermost, as shown in Fig. 2, when hooking the hook-arms H in the eyes K, upon the end of the chair-back, then the nearer of its two ends to the front side of the chair-seat, it can be made firm and secure in such position, and thereby susceptible of being used as a writing desk or table, after which, by simply swinging the chair-back back to and over the seat, first having unhooked the hook-arms therefrom, it can be again brought into proper position for forming the back to the chair-seat A, the chair-back, when in the position shown in Fig. 2, being entirely free of the chair-seat, or, in other words, sufficiently so to allow a person to occupy the same.

L is a drawer arranged upon or in the chair-seat for the reception of paper, envelopes, pen and ink, and other writing-utensils.

I claim as new and desire to secure by Letters Patent—

The combination of the chair-seat A, back E, having eyes K, side arms, D, having eyes J, uprights or supports c, and hook-arms H, or their equivalents, when all connected and arranged so as to allow the back to be swung down into a horizontal position, or nearly so, and there supported, substantially as and for the purposes described.

WILLIAM A. EHLMAN.
